UNITED STATES PATENT OFFICE.

CHRISTEN J. PETERSON, OF CHICAGO, ILLINOIS.

BRISTLE FABRIC AND PROCESS OF MAKING THE SAME.

1,194,874.

Specification of Letters Patent. Patented Aug. 15, 1916.

Application filed May 6, 1915. Serial No. 26,370.

To all whom it may concern:

Be it known that I, CHRISTEN J. PETERSON, a citizen of the United States, residing at Chicago, in the county of Cook and State 5 of Illinois, have invented certain new and useful Improvements in Bristle Fabric and Processes of Making the Same, of which the following is a specification.

The present invention relates to a bristle 10 fabric, such, for instance, as a door mat made of cocoa fiber, or other suitable material, together with a process of making such fabric.

The objects of the invention are to utilize 15 a continuously acting process for the purpose of manufacturing a bristle fabric, thereby materially cheapening and expediting the manufacture of such a product; to produce a product which is more sanitary 20 and just as strong and durable as the product now made for such purposes; and to employ the same material which binds the bristle together into a single mass to affix or adhere a backing to such mass.

25 The invention further consists in the features of construction and combinations of parts hereinafter described and claimed.

In the drawings: Figure 1 is a diagrammatic view of an apparatus for carrying out 30 the process of the present invention; Fig. 2 is a section on line 2—2 of Fig. 1, looking in the direction of the arrow; Fig. 3 is a side view of a somewhat modified form of feeding mechanism; and Fig. 4 is a cross section of a piece of the completed product of 35 the present invention.

In the art to which the present invention relates, namely, the manufacture of bristle fabric, as, for instance, cocoa mats, these 40 mats have been universally made, so far as I am aware, by a weaving process; that is, by using woof and warp threads which are beaten up by a loom, for the purpose of interweaving and locking in place a series 45 of tufts of cocoa fibers. These tufts are laid close together and woven tightly in place to form the bristle surface of the mat.

The foregoing process is somewhat expensive and requires a considerable amount of 50 hand-work.

In the present invention by a novel process, this now-employed method of manufacture is dispensed with and a cheaper and more efficient method disclosed. I desire to 55 state, at this point, that, although for the

sake of clearness and expedition, I shall confine the following description of the process and product to a cocoa mat, nevertheless it is to be understood that the process is capable of use for the purpose of producing other things than mats, and that I claim for my invention an original process of producing a bristle fabric, together with the product thereof, which bristle fabric, according to the material employed and its 60 form and shape, may be adapted for the manufacture of brushes or other articles usually formed of a bristle material.

Referring first to the process of manufacturing, I employ a trough-like receptacle 70 5 of suitable size and construction, into which is fed, by a reciprocating plunger 6 operated by any suitable means, a quantity of cut bristle, and in the construction shown in Fig. 1, a series of cord or string 7 of suitable material is fed from a coil or reel 8 by feed rolls 9 in a downward direction. A movable cutting member 10 is shown as carried by the packing member 6, which movable cutting member coöperates with a fixed 75 cutting member 11 to sever the bristles at the line of cutting action. These bristles, when severed, are forced forward by the reciprocating plunger 6 through a swinging gate member 12, and thence into the chamber 75 80 85 90 95 100 105 110

At the initial operation of the device, I place some suitable form of backing member, as, for instance, a block 13 in front of the bristle being forced into the chamber 5. 90 This is merely for the purpose of maintaining the bristle in an upright condition within this chamber until a start is made in forming the complete product. The bristle is forced forward, and in such forward travel, passes beneath the open end 14 of a spout 15 leading from a tank 16 which is filled with some suitable kind of cementitious compound preferably of an asphaltum nature. The end of the spout, as will be apparent from Fig. 1, projects slightly into the mass of bristle, so that as the bristle passes beneath the spout, they are separated; that is, those to the rear of the spout are slightly flexed backward, as will be seen from Fig. 1. 100 Through the open end of this spout, passes a stream of the cementitious compound herefore referred to, and it is obvious that by opening up the mass of bristle in the manner specified, this compound will percolate down 110

for a distance and into the mass of bristle lying within the trough 5, and spreading the substance about the upper part of such mass.

5 By opening up the bristle in the manner described, the cementitious composition will flow entirely around and through the upper end of the mass, so that the upper part of each of the bristles of the mass will become 10 coated with this cementitious composition. The composition is one which is in a pasty or adhesive condition when applied, but when it becomes hard, it is not affected by the action of moisture, etc. In fact, it becomes, as 15 stated, a cementitious composition.

Located beyond the tank 16 is a roll 17 from which is unwound a backing strip 18 which may be in the nature of roofing felt or other suitable composition. This backing 20 strip passes off from the roll 17 beneath a pressure roller 19, and by the action of this latter roller is pressed into engagement with the upper end of the mass of bristle passing through the chamber 5.

25 As will be seen from Fig. 1, the point of application of the backing member is close to the point of application of the cementitious composition, and hence the backing strip is applied to the mass of bristle, while the 30 cementitious composition previously applied thereto is in a plastic state and the backing strip will thus become fixedly and securely adhered to said mass. The application of this backing strip marks the completion of 35 the product, and after it has been carried on and dried so that the cementitious composition is set, it can then be cut into any length and shape desired.

In order to assist in the carrying of the 40 material through the machine, an endless member 20 is employed, driven by some suitable means, which member carries the completed product onward. This endless member is timed to work in synchronism 45 with the plunger 6, so that it feeds the work forward in correspondence to the placing of the new bristles within the trough 5, and the endless member is employed in order that the entire work of forcing the material 50 through the machine against the pressure of the roller 19 will not fall upon the plunger 6. This endless member, therefore, is simply a supplemental feeding member.

When the product has been suitably dried 55 so that the cementitious composition is hardened, it will have the appearance of the section or piece, shown in Fig. 4, and as shown, will consist of a mass of bristle 21 joined together at their inner ends by a cementitious composition 22, so that their 60 ends are really set in cement, and affixed by this same cementitious composition is the backing strip 23. This form of product will be found to be durable as to wear, and will 65 also be found to be of a more sanitary na-

ture than the old style of mat, since the bristles are not drawn down together at their inner ends, but are lying the same distance apart from their inner to their outer ends, and hence any dirt that may get into 70 the mat can be easily shaken loose, since there will be no tightly drawn portion at the bottom of the mat which would tend to retain the dirt when it has worked into the crevices of such tightly drawn or compact 75 position.

As stated in the preamble, although the description of the invention for the sake of brevity has been directed almost entirely, to the use of the present process for making 80 a new form of bristle mat, the process may be obviously adopted for use in making other bristle fabrics which would be employed in the manufacture of brushes, etc.

In Fig. 3 is shown a modified feed device 85 which is intended to be used when hair bristles are employed. This consists of a magazine 21^a from which depends a spout or series of spouts 22^a, and feed rolls 23^a are used for the purpose of forcing the hair 90 through these spouts and into position to be severed by the cutting mechanism. Should some of the hairs which are fed into the receptacle 5 be too short to receive any 95 of the adhesive substance, they can be eliminated from the mat structure by a shaking of the same after it has been formed. In other respects, the process of forming the bristle fabric from hair is the same as described in connection with the manufacture 100 of cocoa mat.

I claim:

1. The process of manufacturing bristle fabric which consists in first cutting the bristles into uniform lengths, then treating 105 one end of each bristle to an application of cementitious material, then applying a backing piece to the cementitious treated ends of the bristle while the cement is in plastic condition, and in maintaining the bristles 110 in upright position with reference to the backing piece during the hardening of the cementitious material, substantially as described.

2. The process of manufacturing bristle 115 fabric which consists in feeding bristles of uniform length into a receptacle, then embedding one end of each bristle in a cementitious material, then applying a backing piece over the cementitious embedded ends 120 of the bristles while the cement is in plastic condition, and then allowing the cementitious material to harden, substantially as described.

3. The process of manufacturing bristle 125 fabric which consists in feeding bristles into a receptacle, then cutting the bristles into uniform lengths, then subjecting one end of the bristles to an application of cementitious material, then applying a backing piece to 130

the cementitious treated ends while the cement is in plastic condition, and then drying the work, substantially as described.

4. The process of manufacturing a bristle fabric which consists in flexing one end of the bristle, then applying a cementitious composition to said end while the bristles are in flexed condition, then allowing the bristles to straighten, and then applying a 10 backing strip to the cementitious treated ends, substantially as described.

5. The process of manufacturing bristle fabric which consists in placing the bristle within a receptacle, then flexing one end of the bristle, then applying a cementitious composition to said end while the bristles are in flexed condition, then allowing the bristles to straighten, and then applying a 15 backing strip to the cementitious treated ends, substantially as described.

6. The process of manufacturing bristle fabric which consists in feeding bristles into a receptacle, then flexing one end of the bristles, then applying a cementitious composition to said end while the bristles are 20 in flexed condition, then allowing the bristles to straighten, and then applying a backing piece to the cementitious treated ends, substantially as described.

30 7. The process of manufacturing bristle fabric which consists in cutting the bristles to a desired length, then placing them within a receptacle, then flexing one end of the bristles, then applying a cementitious composition to said end while the bristles are 35 in flexed condition, and then applying a backing strip to the cementitious treated ends, substantially as described.

8. The process of manufacturing bristle 40 fabric which consists in flexing one end of

the bristles, then applying a cementitious compound to said end while the bristles are in flexed condition, and then allowing the bristle to straighten, substantially as described.

45

9. The process of manufacturing bristle fabric which consists first in cutting the bristles to a desired size, then flexing one end of the bristles, then applying a cementitious compound to said end while the 50 bristles are in flexed condition, and then allowing the bristle to straighten, substantially as described.

10. As a new article of manufacture, a bristle fabric comprising a backing member, 55 bristles outstanding therefrom, and adhesive means for securing each bristle to the surface of the backing member, substantially as described.

11. As a new article of manufacture, a 60 bristle fabric comprising a backing member, bristles outstanding therefrom, and adhesive means within which a part of each bristle is embedded, whereby it is secured to the surface of the backing member, 65 substantially as described.

12. As a new article of manufacture, a bristle fabric comprising a bristle retaining member and a brushing member, the bristle retaining member consisting solely of a flexible adhesive mass and the brushing member consisting of a bristle mass outstanding from the adhesive mass with a portion of each bristle embedded partly through the adhesive mass, substantially as described.
